Primary Examiner — Garth Rademaker*Assistant Examiner* — Suzanne E Tisdell(74) *Attorney, Agent, or Firm* — Hoffman Warnick LLC(57) **CLAIM**

The ornamental design for a canopy support, as shown and described.

DESCRIPTION

FIG. 1 is a side view of the first embodiment of a canopy support, placed in series.

FIG. 2 is a side view of a single element of the canopy support.

FIG. 3 is a top perspective view of the support, covered with a canopy.

FIG. 4 is a top perspective view of the uncovered support.

FIG. 5 is a rear view of FIG. 4 with the crossbeams omitted.

FIG. 6 is a side, perspective, elevated view of the top of the connecting bracket of the support without crossbeams.

FIG. 7 is a perspective, elevated detail view of the side of the connecting bracket of the support, without crossbeams; and,

FIG. 8 is a top perspective view of the second embodiment of an uncovered canopy support.

The broken lines in the figures depict subject matter that forms no part of the claimed design.

1 Claim, 6 Drawing Sheets(56)
